UNITED STATES PATENT OFFICE.

AUGUST BOOS, OF NEW YORK, N. Y., ASSIGNOR OF ONE-TENTH TO FRANK M. ASHELEY, OF NEW YORK, N. Y.

TIME-STAMP.

No. 852,818.

Specification of Letters Patent.

Patented May 7, 1907.

Application filed December 22, 1904. Serial No. 237,898.

To all whom it may concern:

Be it known that I, AUGUST BOOS, a subject of the Emperor of Germany, and a resident of the borough of Manhattan, in the county of New York and State of New York, have invented a new and useful Improvement in Time-Stamp, of which the following is a specification.

My present invention pertains to stamping devices, which, being properly operated, may impress upon suitable material a record of the particular year, month, day, hour and minute when the impression was made.

The object of my invention is to provide more reliable and more effective mechanism for the purpose referred to.

In the drawing, Figure 1 is a front elevation of parts of recording and impressing mechanism; parts of an inclosing case being removed therefrom; Fig. 2 is a vertical transverse section of a part of a crown ratchet-wheel and of a part of a minute wheel; Fig. 3 is a front elevation of an hour wheel; Fig. 4 is a rear elevation of an hour wheel and of a spring detent and its support; Fig. 5 is an elevation of a detent; Fig. 6 is an elevation of parts of minute-recording mechanism; Fig. 7 is a perspective end elevation of inking mechanism, and of a stand in which said mechanism is mounted; Fig. 8 is a view, partly in section and partly in elevation, of parts of impressing mechanism; Fig. 9 is a perspective view of a check-holding slide; Fig. 10 is a side elevation of a shaft, and of part of another shaft which carries a spur pinion; Fig. 11 is a top plan view of a blank check, and Fig. 12 is a similar view of a check bearing a time record.

Reference characters are relatively alike throughout the drawings.

Inclosed within a suitable case *a*, is a frame *b*, and mounted within said casing and frame is a clock movement which may comprise any mechanism suitable for the purpose, and is indicated herein, in a general way, by the reference mark *c*. The main spindle *d*, of the clock movement *c*, extends through the frame *b*, and mounted in axial alignment therewith is a separable spindle *i*, on the latter of which is rigidly mounted a drum *e*, adapted to rotate therewith. A spring *f*, herein shown as helical in form, is partially inclosed in the drum *e*, and its outer end contacts a crown ratchet-wheel *g*, and

urges it into mesh with a similar ratchet-wheel *h*, herein termed a "minute-wheel," which is of the same pitch and number of teeth, but is of greater diameter than the wheel *g*. The latter is slidable axially of and is rotated by the spindle *i*, and the teeth of the crown ratchet-wheel *g*, slidingly engage those of the minute-wheel *h*, which latter is loosely mounted upon the same spindle. Rigidly secured upon and rotating with the separable spindle *i*, is a hub *j*, from which project one or more radial arms *k*; the arms being, preferably, equal in number to arms *m*, which connect the rim of the wheel *h*, to the hub thereof. Mounted upon each arm *m*, is a resilient member, herein shown as a spring *n*, which contacts an arm *k*, of the hub *j*, and may urge the wheel *h*, to rotate in the direction in which the hub *j*, rotates. On the minute-wheel *h*, is fixed a rim *o*, on the face of which are fixed minute-type which may respectively impress numbers from "1" to "59," both inclusive, and a double cipher, ".00." On the intermediate plate of the frame *b*, is mounted a reciprocatable detent *p*, which is engageable with the teeth of the minute-wheel *h*, and resilient means, herein shown as a spring *q*, urges the detent *p*, into engagement as aforesaid. On the detent *p*, is formed a lug *r*, which contacts the outer edge of the rim of the wheel *g*. It should be noted that the direction of rotation of the spindles *d*, *i*, and consequently of the drum *e*, spring *f*, and wheel *g*, is clockwise.

In a standard *s*, which is fixed to the frame *b*, is fixed a stud *t*, upon which is rotatably mounted an hour-wheel *u*, on the rim of which are mounted twelve hour-type, each of which is adapted to make an impression of a numeral which represents one of the twelve hours. On one face of the wheel *u*, is secured a disk having recesses *v*, adapted in form, dimensions and relative positions, to operate, as hereinafter related, in combination with a spring-detent *w*; the free end of said spring-detent being adapted in form and dimensions to coact with the recessed parts. The recesses *v*, should equal in number certain type *x*, which are fixed upon the other part of the rim of the wheel *u*, said type being hereinafter referred to as hour-type; and the angular relation of said hour-type to the recesses *v*, should be such that one of said type will be in its impressing position when the spring *w*, is prop-

erly engaged in one of the recesses *v*. On the hour-wheel *u*, are fixed twelve teeth *y*, *y*, which project axially from said wheel; and on the minute-wheel *h*, is fixed a tappet *z*, which, at the proper point in the rotation of the wheel *h*, is engageable with one of the teeth *y*. The relations of the teeth *y*, tappet *z*, and wheel *h*, and the minute-type from "00" to "59", which are mounted on the latter, should be such that when the particular minute-type "00," is about to be brought to the impressing point, the tappet *z*, will engage one of the teeth *y*, so that a continued movement of the wheel *h*, during which movement the minute-type "00", would be arriving at the impressing point, would cause the hour-wheel *u*, to rotate sufficiently to disengage the spring-detent *w*, from the particular notch *v*, in which it had been engaged and to cause said detent to become engaged in the forward part of the next succeeding notch *v*.

In proper sequence, below, and attached to, the frame *b*, are removable type, herein shown as five in number, and arranged to make impressions upon a plane with the impressions of the minute and hour-type; which, beginning with a type herein referred to as 1, and including type herein referred to as 2, 3, 4 and 5, may, respectively, be as follows; namely, "O' C", an abbreviation of the name of a week day, an abbreviation of the name of a month, the ordinal of a day of a month, and the ordinal of a year.

An impression device is arranged to press impression-receptive material against the minute-type, hour-type and removable type; and may be described as follows: In the lower part of the frame *b*, may be inserted a slide 6, on the under side of which a hand-lever 7, is pivotally mounted. An impression pad 8, is attached to the end of the lever 7, opposite to the handle thereof. The slide 6, is adapted to receive impression-receptive material, herein shown as a check 9; and clamps 10, 10, to hold the check 9, in position, are attached to the upper side of the slide 6. Ways 11, 11, are provided in a stand 12, in which the slide 6, may be slid. An inking-pad 13, is so mounted in the stand 12, as to be reciprocatable transversely of the latter, and is supported upon springs 14, 14, which rest upon a cross piece 15, which is fixed in the stand 12. A beveled cleat 16, is fixed at each end of the ink-pad 13, and is engageable on each of its beveled surfaces by one of two beveled faces 17, 17, which are respectively formed near each side of the slide 6. Spring operated strippers 18, 18, are arranged to strip a stamped check from the type *z*, and *o*, and 1, to 5, inclusive; all of said type being simultaneously operative. A spring 19, may be provided to urge the end of the lever 7, with the attached impression pad 8, downwardly, or away from the before-mentioned type.

The time-stamp mechanism thus described may be operated as follows: The main spindle *d*, may be rotated by the clock movement *c*, which may be operated by any suitable power, a spring-urged drum 20, to which is fixed a spur-gear wheel 21, which meshes with a spur-pinion 22, which is fixed upon the main spindle *d*, being shown herein for the purpose mentioned. With the spindle *d*, may be rotated the drum *e*, the spring *f*, and also the ratchet-wheel *g*; the rate of rotation being adjusted so that the wheel *g*, will make one complete revolution in each hour, and will therefore rotate to the angular distance of six degrees, or of one tooth of the ratchet-wheel, in each minute. The spring *g*, will cause the reciprocatable detent *p*, to engage a tooth of the wheel *h*, and thus prevent the latter from being rotated by the wheel *g*. Consequently the rotation of the wheel *g*, by reason of the movement of its ratchet-teeth upon the ratchet-teeth of the wheel *h*, will be caused to move axially of the spindle *d*, and against the pressure of the spring *f*; and in said axial movement will, by means of the lug *r*, move the detent *p*, in the same direction, and thus disengage the latter from the wheel *h*. When the axial movement of the wheel *g* is sufficient for the disengagement of the detent *p* from the wheel *h*, the latter will be partially rotated by reason of the resilient pressure exerted upon the arms *k*, by the springs *n*, which are attached to the arms *m*, of the wheel *h*; but immediately after the commencement of the rotation of the wheel *h*, the spring *f*, will be permitted to urge the wheel *g*, axially of the spindle *d*, and in a direction contrary to that of its former axial movement, and the teeth of the wheel *g*, will thus, be made to engage with axial faces of the teeth of the wheel *h*; thereby limiting the rotation of the latter to the angular distance of six degrees, or to the extent of one tooth, at which time the detent *p*, will also have engaged a tooth of the wheel *h*, and will thereby prevent further rotation of the latter. It is not necessary that the wheel *g*, should have the exact number of teeth shown and hereinbefore mentioned, as three or more teeth, which should be evenly distributed on the side of the wheel, will answer the purpose quite as well as sixty. When the rotation of the wheel *h*, has brought the minute-type "59," to the impression point, the tappet *z*, will contact one of the teeth *y*, so that the next partial rotation of the wheel *h*, which, as before related, will bring the minute-type "00," to the impression point, will also cause the tappet *z*, to rotate the wheel *u*, sufficiently to disengage the spring-detent *w*, from the particular recess *v*, in which it had been engaged and will also cause said detent *w*, to engage in the forward part of the next succeeding recess *v*. If the faces of the recesses *v*, be cam-shaped, as shown in the

drawing, the detent *w*, will cause the hour-wheel *u*, to continue to rotate until it has made one-twelfth of a full turn; when the detent *w*, will resiliently engage both surfaces 5 in the recess *v*; an hour-type *x*, will then be at the proper impressing point; and accidental rotary movement of the hour-wheel *u*, will be prevented by the engagement of the spring-detent *w*, in the recess *v*, as before related. The check 9, which has received certain impressions as before related, may now be placed in the slide 6, which may have been slid outwardly of the ways 11, in order to receive the check 9; the latter being retained 15 in position in the former by means of the clamps 10, 10. The slide 6, may then be slid inwardly of the stand 12, during which movement the bevel faces 17, of the slide 6, will engage the bevel cleats 16, and thus force the 20 ink pad 13, downwardly, in which position the slide 6, will maintain said ink pad for the time being. The check 9, being properly positioned under the stamps *x*, and *o*, and 1, to 5, inclusively, the hand lever 7, may be 25 depressed, and thus, by means of the impression pad 8, press the check 9, against said type, and the latter will thus be caused to impress upon the check 9, the letters "O' C;" the time, in hours and minutes; the name 30 of a day of the week; the name of a month, and the ordinal of a day of a month. When the check has been impressed as before described, the handle 7, may be raised, and the impression pad 8, will thus be withdrawn 35 from its impressing position, while the check 9, will be withdrawn by the strippers 18, from contact with the impressing faces.

I claim as new and as my invention,

1. In a recording mechanism, the combination of a clock movement which operates a main spindle; said main spindle; a spring-urged crown ratchet-wheel which is slidable axially of and is rotatable by the main spindle; a separable spindle which is mounted in alinement with and is rotatable by the main spindle; a minute ratchet-wheel which is loosely mounted upon the separable spindle and the teeth of which are slidably engageable by those of the crown ratchet-wheel; 45 minute-type which are fixed upon the minute-wheel; a radially-armed hub which is rigidly mounted upon the separable spindle; at least one resilient member which is mounted upon the radially-armed hub and urges the minute-wheel rotatably; and a detent which is engageable with a tooth of the minute-wheel and is disengageable from said tooth by an axial movement of the crown ratchet-wheel.

2. In a recording mechanism, the combination of a clock movement which operates a main spindle; said main spindle; a spring-urged crown ratchet-wheel which is slidable axially of and is rotatable by the main spindle; a separable spindle which is mounted in 55 alinement with and is rotatable by the main

spindle; a minute ratchet-wheel which is loosely mounted upon the separable spindle and the teeth of which are slidably engageable by those of the crown ratchet-wheel; minute-type which are fixed upon the minute-wheel; a radially-armed hub which is rigidly mounted upon the separable spindle; at least one resilient member which is mounted upon the radially-armed hub and urges the minute-wheel rotatably; a detent which is engageable with a tooth of the minute-wheel and is disengageable from said tooth by an axial movement of the crown ratchet-wheel; and resilient means which are arranged to urge the detent into engagement with a tooth of the minute-wheel.

3. In a recording mechanism, the combination of a separate spindle; a crown ratchet-wheel; a minute ratchet-wheel which is loosely mounted upon the separable spindle and the teeth of which are slidably engageable by those of the crown ratchet-wheel; minute-type which are fixed upon the minute-wheel; an hour-wheel; hour-type which are mounted on the hour-wheel; and removable type which are arranged to impress on a plane with impressions of the minute-type and hour-type.

4. In a recording mechanism, the combination of a separate spindle; a crown ratchet-wheel; a minute ratchet-wheel which is loosely mounted upon the separable spindle and the teeth of which are slidably engageable by those of the crown ratchet-wheel; minute-type which are fixed upon the minute-wheel; an hour-wheel; hour-type which are mounted on the hour-wheel; removable type which are arranged to impress on a plane with impressions of the minute-type and hour-type; and an impression device which is arranged to press impression-receptive material against the minute-type, hour-type and removable type.

5. In a recording mechanism, the combination of a separate spindle; a crown ratchet-wheel; a minute-ratchet-wheel which is loosely mounted upon the separable spindle and the teeth of which are slidably engageable by those of the crown ratchet-wheel; minute-type which are fixed upon the minute-wheel; an hour-wheel; hour-type which are mounted on the hour-wheel; removable type which are arranged to impress on a plane with impressions of the minute-type and hour-type; an impression device which is arranged to press impression-receptive material against the minute-type, hour-type and removable type; a stand in which the impression device is slidably mounted; and an inking-pad which is reciprocatively mounted in said stand and is contactible with the minute-type, the hour-type and the removable type.

6. In a recording mechanism, the combination of a separate spindle; a crown ratchet-

wheel; a minute ratchet-wheel which is loosely mounted upon the separable spindle and the teeth of which are slidingly engageable by those of the crown ratchet-wheel; 5 minute-type which are fixed upon the minute-wheel; an hour-wheel; hour-type which are mounted on the hour-wheel; removable type which are arranged to impress on a plane with impressions of the minute-type 10 and hour-type; an impression device which is arranged to press impression-receptive material against the minute-type, hour-type and removable type; a stand in which the impression device is slidably mounted; an

inking-pad which is reciprocatively mounted 15 in said stand and is contactible with the minute-type, the hour-type and the removable type; and means which are attached to the inking-pad and to the impression device by which the inking-pad may be withdrawn 20 from the type.

In testimony whereof I have signed my name to this application in the presence of two subscribing witnesses.

AUGUST BOOS.

CHAS. H. DAVIDS,
PIERSON L. WELLS.

It is hereby certified that the name of the assignee in Letters Patent No. 852,818, granted May 7, 1907, upon the application of August Boos, of New York, N. Y., for an improvement in "Time-Stamp," was erroneously written and printed "Frank M. Asheley," whereas said name should have been written and printed *Frank M. Ashley*; and that the said Letters Patent should be read with this correction therein that the same may conform to the record of the case in the Patent Office.

Signed and sealed this 4th day of June, A. D., 1907.

[SEAL.]

E. B. MOORE,
Commissioner of Patents.
